UNITED STATES PATENT OFFICE.

ALFRED BARBOUR, OF TARENTUM, PENNSYLVANIA.

PIPE-WRENCH.

SPECIFICATION forming part of Letters Patent No. 307,830, dated November 11, 1884.

Application filed April 17, 1883. (No model.)

To all whom it may concern:

Be it known that I, ALFRED BARBOUR, a subject of the Queen of Great Britain, residing at Tarentum, in the county of Allegheny 5 and State of Pennsylvania, have invented certain new and useful Improvements in Pipe-Wrenches, of which the following is a specification, reference being had therein to the accompanying drawings.

10 Figure 1 represents a side elevation of a style of nut or pipe wrench to which I have applied my pipe-cutting tool in combination therewith. Fig. 2 is an elevation, partly in section, of the style of wrench shown in Fig. 1, exhibiting the pipe-cutter attached thereto, with the necessary modifications which adapt it for use as a combination-tool.

15 My invention relates to pipe wrenches or tongs; and it consists in the combination and arrangement of levers constituting a wrench of the self-adjusting order with a pipe-cutter combined. A detailed description of it will be given, and the points of novelty believed to be new will be set forth in the claim.

20 A represents the wrench, composed of the lever *a*, fulcrumed at *a'*, and the link *b*, pivoted to the fulcrum-point of the lever. The short arm *c* of the lever *a* is segment-shaped and provided with a serrated gripping-face arranged to swing outwardly from the hook-link *b* when engaging the pipe to be operated upon, and inwardly when it is desired to release the pipe. The link *b* is bifurcated, so as to embrace the lever *a*, and so that the latter may 25 swing freely through it. It is also preferably provided with an angular recess in its outer

end, which serves to hold the pipe more firmly in place.

The construction of the pipe or nut wrench heretofore described I have devised to be used 40 in combination with a pipe-cutter, as shown in Fig. 2, and which I claim as my invention. The lever *a* *a'* is constructed in two parts, one of which, *a'*, carries a clamping-jaw, *c'*, opposite the segmental gripper *c*, and a female 45 threaded socket, into which the other part or lever-handle, *a*, enters with its screw-thread *d*. Surrounding the two parts of the lever is a sleeve, *B*, carrying the cutter-wheel *D*, the adjustment of which is secured for cutting the 50 pipe by the revolution of the lever-handle within the screw-socket, the shoulder *e* of the lever forcing the sleeve *B* and its wheel into contact continuously as the pipe is cut.

Having described my invention, what I claim 55 as new, and desire to secure by Letters Patent, is—

As a new article of manufacture, a combined nut or pipe wrench and cutter, the operating-lever comprising two parts, *a* *a'*, one of which, 60 *a'*, carries the hook-link *b*, gripper *c*, and jaw *c'*, and the surrounding sleeve *B*, carrying cutter *D*, the sleeve having its adjustment secured by the screw-connection of the two parts of the lever, substantially as set forth. 65

In testimony whereof I affix my signature in presence of two witnesses.

ALFRED BARBOUR.
